UNITED STATES PATENT OFFICE.

JOSEPH MATTHEWS AND EDWARD W. FREEMAN, OF PHILADELPHIA, PENNSYLVANIA, ASSIGNORS TO MCFARLAND-MEADE COMPANY, OF PHILADELPHIA, PENNSYLVANIA, A CORPORATION OF PENNSYLVANIA.

WINDOW-OPERATING MECHANISM.

Application filed March 29, 1922. Serial No. 547,636.

Our invention relates to window operating mechanism of the type which is adapted to simultaneously open and close a number of windows or ventilators arranged in a row 5 in spaced or distant relation with respect to each other.

The general object of the invention is to provide not only a strong and durable construction of the character indicated but one 10 which may be operated readily by the application of a minimum amount of power; also one which is efficient in operation.

To these and other ends our invention comprehends the construction as hereinafter 15 fully described, particularly pointed out and defined in the claims and as illustrated in the drawings constituting a part of this specification, and in which—

Fig. 1 is a view showing a portion of a 20 window in horizontal section and also showing the mechanism embodying our invention partly in plan and partly in horizontal section;

Fig. 2 is a front elevation showing the 25 means by which the mechanism is adapted to be operated;

Fig. 3 is a vertical sectional view taken on the line 3—3 of Fig. 1;

Fig. 4 is a perspective view of the means 30 for pivotally supporting the mechanism in operative relation with respect to the windows;

Fig. 5 is a perspective view of an arm 35 which is adapted to be pivotally connected to the left hand portion of the support shown in Fig. 4;

Fig. 6 is a view showing in detail the manner in which the window operating links 40 are connected to the outer ends of the arms, one of which is shown in Fig. 5; and

Fig. 7 is a vertical sectional view showing the manner in which the outer ends of the operating levers of the mechanism are connected to the operating rods or bars of the 45 mechanism.

In the drawings we have shown a preferred form of construction embodying our invention, but it will be understood that said invention is susceptible of embodiment 50 in other forms of construction than that shown and that various changes in the details of construction may be made within the scope of the claims hereunto appended without departing from said invention.

Referring in detail to the drawings: 1 55 designates as a whole the sash of a window by which the pane 2 of glass or other suitable transparent material is supported.

Constructions of the character to which our invention relates are usually employed for 60 operating relatively wide windows or ventilators in factory buildings in which the window sashes are of iron or other suitable metal and which are heavy, in consequence of which two or more sets of operating 65 means are usually employed for the opening or closing of each window or ventilator although this is not essential. In the construction illustrated we have shown two sets of mechanism both of which are employed 70 for the operation of a single window. One set of the said mechanism is held and supported in reversed position with respect to the other. Both sets of mechanism are supported upon a short channel member 3 secured to a column or post 4, which comprises angle plates, as shown, by means of bolts 5. The said channel member is provided with outwardly extending brackets 7 and 8, the former being connected to one 80 end portion of the lower flange of the channel member 3 while the other is connected to the opposite end portion of the upper flange of said channel member. Such connection is in part effected by means of rivets 75 9. Operating levers 11 and 12 are pivotally connected intermediate their ends by means of pivots 13 to the outer ends of the respective brackets 7 and 8. The outer ends of these levers 11 and 12 are pivotally connected to the respective operating or actuating rods 14 and 15. For the purpose of adjustably or pivotally connecting these rods to the outer ends of said levers, we have provided each of the said levers with an 90 opening 15^a in which is journaled a boss or projection 16 which extends downwardly from the base 17 of an angle member 18 having an upright portion 19 which is provided with an inwardly extending over-hanging 95 flange portion 20. The said base is provided with an opening 21 which extends through the boss 16 and is also provided with a V-shaped notch 22 which extends transversely thereof, as shown in Fig. 7. Co-operating 100 with the said angle member 18 is a clamping and holding block 23 provided with a notch 26 at its outer upper edge portion and also

with an opening 27 adapted to be placed in alignment with the opening 21. The inwardly extending over-hanging projection 20 is adapted to be seated within the notch 26. The block is provided upon its under side with a notch 28 which faces the notch 22. The operating or actuating rods 14 and 15 are adapted to be located in these notches and clamped and held between the blocks 25 and the bases 17 of the angle members 18. Bolts 30 extend through the base 17, the block 25 and the outer end of the levers 11 and 12 and the nuts and washers 31 on the opposite ends thereof operate to clamp and hold the blocks 25 against the actuating or operating rods 11 and 12 and also to secure the same together with the said blocks and angle members 25 and 18 to the said levers.

The respective sets of mechanism comprise arms 35 and 36, the former being situated in a plane below the latter. Each of the arms 35 is supported and strengthened by the angular bracing member 37 while each of the arms 36 is supported and strengthened by the angular bracing member 38. The arm 35 with its angle member 37 is pivotally connected to the left hand end portion of the channel 3 by means of a bolt 40 while the arm 36 with its brace 38 is pivoted to the opposite end portion of the channel 3 by means of a pivot bolt 41. The bolts 40 and 41 extend vertically through the flanges of the said channel member and constitute additional means for securing the brackets 7 and 8 to the flanges of the channel member 3.

The inner ends of the pivot levers 11 and 12 beyond their pivots 13 are pivotally connected to the inner ends of links 42 and 43 while the outer ends of the latter are pivotally connected to the arms 35 and 36 at points intermediate their ends. It will be noted that the pivots 13 are situated very much nearer to the inner ends of the levers 11 and 12 than they are to their outer ends; and also that the outer ends of the links 42 and 43 are connected substantially nearer to the pivots 40 and 41 of the arms 35 and 36 than to the outer ends of the said arms. The outer ends of the arms 35 and 36 are connected to the outer ends of links 45 which are in turn pivotally connected at their inner ends to brackets or lugs 46 which are secured to the bottom sash of the window. The connection to the brackets or lugs 46 is effected by means of bolts 47.

Connection between the ends of the links 45 and the outer ends of the arms 35 and 36 is effected by means of bolts 50 which extend through openings 51 in the outer ends of said links and arms, which bolts are provided with bearing sleeves 52 which are of oval shape as indicated in Fig. 6. These bearing sleeves are mounted upon the bolts 50 and are interposed between the same and

the walls of the said openings. The bolts are retained in position by means of the nuts and washers 53. The presence of the oval sleeves permits relative rocking movement between the links 45 and the arms 35 or 36 as the case may be.

The positions of the pivots 13 with relation to the inner and outer ends of the levers 11 and 12 and the relation of the points of connection of the links 42 and 43 to the arms 35 and 36 to the opposite ends of the latter and the relation of the length of the said links 42 and 43 to the portions of the levers 11 and 12 inwardly of the pivots 13 should be such as to utilize as efficiently as possible the power applied to operate the mechanism to open and close the windows or ventilators.

The opposite ends of the operating or actuating rods 14 and 15 are connected by means of sprocket chains 60 and 61 which are mounted on the sprocket wheel 62 and wheel 63 supported upon shafts 64 and 65; also supported upon the shaft 64 is a worm gear 66 with which is engaged a worm 67 mounted upon a shaft 68 journaled in bearings 69. A pulley or sheave 70 is also supported upon the shaft 68 and is adapted to be driven by a cord or band 71. By rotating the sheave 70 in one direction or the other the sprocket wheel 62 through the worm 67 is rotated in a corresponding direction to actuate the sprocket chain 60 and cause horizontal longitudinal movement of the actuating rods 14 and 15 in opposite directions.

Assuming that it is desired to move the levers 11 and 12 from the positions indicated in full lines in Fig. 1 to the dotted line position shown therein, the rods 14 and 15 are actuated in the directions indicated by the arrows 72 and 73. Such movement of the levers 11 and 12 operates through the links 42 and 43 to actuate the arms 35 and 36 which through the links 45 cause opening movement of the window to the dotted line position indicated. The rods 14 and 15 should be moved in the opposite directions to those indicated by the arrows 72 and 73 to return the levers 11 and 12 from the dotted line positions shown in said figure to the full line positions shown to effect closing movement of the window.

It will be seen that we have provided a simple and efficient construction of mechanism which is adapted to operate in a most efficient manner to effect the opening and closing of any number of windows or ventilators simultaneously.

Having thus described our invention, what we claim and desire to secure by Letters Patent is:

1. In window operating means, the combination of a plurality of levers pivotally supported in different horizontal planes at

points intermediate their ends, a plurality of arms pivotally supported at their inner ends, means for connecting the said levers and arms in couples, and means for connecting the outer ends of said arms to a window to open and close the same, the said means and said arm having relative rocking movements.

2. In means for operating a plurality of windows, the combination of a plurality of levers alternate ones of which are situated in different horizontal planes, said levers being pivotally supported at points intermediate their ends, a plurality of arms respectively associated with said levers to form couples therewith, said arms being pivotally supported at their inner ends, links connecting the inner ends of said levers to said arms at points intermediate their ends, connections between the outer ends of said arms and the windows to be operated, and means for simultaneously actuating the levers in the two planes in opposite directions to open or close the said windows.

3. In window operating means, the combination of two series of operating levers pivoted at points intermediate their ends, the said two series being situated in different horizontal planes, two series of arms one series being associated with levers of one series and the other arms being associated with the other series of said levers, the said

arms being pivoted at their inner ends, links connecting the inner ends of said levers to the said arms intermediate the ends of the latter, links connecting the outer ends of said arms to windows arranged in series, and operating means having connection with the outer ends of said levers for simultaneously actuating the levers of one series in one direction and those of the other in the opposite direction to open or close the said windows.

4. In window operating means, the combination of a supporting device having brackets extending forwardly therefrom in different horizontal planes, operating levers pivoted intermediate their ends to said brackets, arms pivoted at their inner ends to the said supporting device, links having connection to the inner ends of the said operating levers and to points intermediate the ends of the said arms, the said points of connection being nearer to the axes of the pivots of said arms than to the outer ends thereof, and links connecting the outer ends of said arms to a window, substantially as described.

In testimony that we claim the foregoing as our invention, we have hereunto signed our names this 4th day of March, 1922.

JOSEPH MATTHEWS.
EDWARD W. FREEMAN.
